MACHINE FOR OPERATING ON HEELS.

1,275,490.

Specification of Letters Patent. Patented Aug. 13, 1918.

Application filed October 4, 1915. Serial No. 53,948.

To all whom it may concern:

Be it known that I, JOHN F. STANDISH, a citizen of the United States, residing at Winthrop, in the county of Essex and State 5 of Massachusetts, have invented certain Improvements in Machines for Operating on Heels, of which the following description, in connection with the accompanying drawings, is a specification, like reference characters 10 on the drawings indicating like parts in the several figures.

This invention relates to machines for operating on heels and is herein shown as embodied in a machine for attaching a heel 15 comprising two sections, one of leather and the other of rubber.

In manufacturing shoes having rubber heels it is the practice to attach to the heel seat portion of the sole a leather or leather- 20 board section or deck which is comparatively incompressible and then, as a separate operation, to attach to the deck the rubber section which, of course, is compressible to a great degree. The first attaching operation 25 is performed by driving nails through the leather deck into the sole and the second attaching operation is performed by driving nails through the rubber section into the previously attached deck. In the second 30 operation the heads of the attaching nails are forced well beneath the outer or tread surface of the rubber section. In both attaching operations the work is subjected to pressure by the operation of the machine. 35 It will be apparent that the movement of the work pressing members necessary to press the leather deck upon the outsole will be much less than that required to exert any considerable pressure upon the combined 40 leather and rubber sections. An object of the present invention is to provide a machine by the use of which heel parts or sections of dissimilar character may be operated upon in such manner as to give the best 45 results in all cases. To this end an important feature of the invention consists in co-operating work pressing members, such as a jack and die plate, and power driven mechanism for moving one of the members 50 through a predetermined distance to press one part of a heel and then automatically through a greater distance to press two or more combined heel parts.

In operating a machine of the character above outlined it might be possible for the 55 operator to start the machine with a leather deck in operative position and when the work pressing mechanism was set for its longer movement which is designed for 60 pressing the combined leather and rubber parts. Under these circumstances an abnormally high pressure would be developed 65 which would be destructive either to the last or to the machine itself. With these conditions in view another feature of the invention consists in means for insuring that the leather heel part alone shall not be subjected to the greater movement of the pressing member. As herein shown this is 70 brought about by providing means which prevent the presentation of the leather deck in operative position when the pressing mechanism is set for the greater pressure movement.

Other features of the invention relate to 75 the jack upon which the shoe is supported in the machine. It will be apparent that the thickness of the work to be operated upon will be much less in the case of the leather deck alone than in the case of the combined 80 leather deck and rubber part. To compensate for this difference the jack herein shown is made adjustable in its height by a predetermined amount and convenient means are 85 provided for effecting such adjustment.

These and other features of the invention will be best understood and appreciated from the following description of a preferred embodiment thereof selected for purposes of illustration and shown in the accompanying drawings, in which,—

Figure 1 is a view in perspective of a machine embodying the invention;

Figs. 2, 3 and 4 are detail views of the pressure regulating mechanism;

Fig. 5 is a view of the machine in front elevation showing the work with pressure applied thereto;

Fig. 6 is a view in perspective of the holder for the heel parts to be attached;

Fig. 7 is a sectional view showing the position of the leather deck and rubber section prior to the operation of attaching the latter;

Fig. 8 is a view in elevation, partly in section, of the jack and associated mechanism;

Fig. 9 is a sectional view showing the jack in a different position from Fig. 8;

Fig. 10 is a detail view of the gage slide, and

5 Fig. 11 shows a portion of a shoe with a leather deck and rubber heel section attached.

10 The invention is herein illustrated as embodied in the well known lightning nailing machine although it will be apparent that its application is in no sense limited to that or to any other particular machine.

15 The machine frame 2 carries at its upper end a stationary die plate 4 provided with passages for the drivers 20. At a point beneath the die plate 4 the frame carries a stationary abutment or support 6 upon which rests the movable jack carriage support 8. The support 8 is arranged 20 to slide vertically in ways formed partly in the machine frame and partly by gibs 10. The support 8 carries the jack carriage 12 which is arranged to slide in the ways above the support 8 and is maintained in position above the support by a quick screw 30 which rests at its lower end upon the support. The jack carriage 12 is provided with substantially horizontal ways for the reception of a jack 14 which is provided with an adjustable heel post 92 and a toe post 95. The shoe to be operated upon is placed upon the jack and the various heel parts are introduced beneath the die plate 4.

25 The machine frame is provided with vertical bearings in which reciprocate a pair of side rods 16 carrying at their upper ends a cross head 18 upon which the drivers 20 are mounted and being connected at their lower ends to a cross head 22 to which movement 30 is imparted from the machine shaft through an eccentric 24.

35 The jack is arranged to be elevated by the operator to subject the work to a measuring pressure preliminarily to the power 40 operation of the machine. To this end the quick screw 30 is provided at its lower end with an elongated pinion arranged to mesh with a rack 32. The rack is connected to a bell crank lever 34 pivoted upon a stud 35 45 set in the stationary abutment 6 and connected through a link 36 to a treadle 38. When the treadle is depressed by the operator the rack is moved toward the left (Figs. 1 and 5) and the screw 30 is turned so as to 50 elevate the jack carriage with respect to the jack carriage support 8. The measuring mechanism herein shown is arranged for manual operation and it is immaterial from the standpoint of the present invention 55 whether such mechanism is manually or mechanically actuated.

60 A pair of eccentric cams 42 and 46 are journaled respectively in the movable support 8 and the stationary abutment 6 and 65 are arranged to be oscillated by the power of

the machine to elevate the support 8 and all the parts above the support in order to subject the work, after the measuring operation, to an increased pressure. The cam 46 is secured to a horizontally extending shaft 43 70 journaled in the stationary abutment 6 and connected at its rear end to a lever 45 to which motion is imparted from the left hand side rod 16 through a collar 50 secured to the rod and a link 48. The cam 42 is secured to a shaft 40 journaled in the movable support 8 and similarly operated from the right hand side rod. It will be understood that in the downward movement 75 of the cross head the cams are oscillated in the direction shown by the arrow in Fig. 3 and Fig. 4 so that the eccentric parts of cams roll together and consequently elevate the support 8.

80 The initial position in the machine of support 8 is determined by an adjustable stop 52 threaded into the lower side of the support and arranged to bear upon the upper surface of the abutment 6. It will be seen that by turning the stop 52 into or out of the movable support 8 the latter may be raised or lowered and consequently the effective movement imparted to the support 8 by the action of the cams 42 and 46 may be regulated. If, for example, the throw of 85 the cams is one-half an inch and the stop 52 is set for an initial separation of one-quarter of an inch the movement imparted to the support 8 will be only one-quarter of an inch. On the other hand, if the stop 52 is 90 so adjusted that the initial separation is 0 then the cams will be effective in imparting a movement of one-half an inch to the support.

95 The support 8 is provided with an outwardly extending boss in which is adjustably received a second stop 54 which is arranged somewhat in advance of the front surface of the stationary abutment 6 but in operative relation to the inner end of a short 100 supporting lever 58 pivotally mounted in the abutment 6. The lever 58 carries at its inner end a roller 60 arranged to bear upon the periphery of a notched cam disk 56 arranged to turn loosely upon the outer end 105 of the shaft 43 above referred to. The cam disk 56 is so designed that when the roller 60 rests in one of its notches the inner end of the lever 58 will stand below the end of the stop 54 so that the stop 52 first mentioned will be effective in determining the 110 position of the support 8. However when the roller 60 rests upon one of the high portions of the cam disk 56 the stop 54 becomes effective to determine the initial position of 115 the support 8, holding the stop 52 above the abutment 6 as shown in Fig. 3. It will thus be seen that the position of the lever 58 120 determines which one of the stops 52 or 54 is to control the initial position of the sup- 125 130

port 8 and as will be presently described, the lever 58 is so operated as to make the first one stop and then the other operative in alternate cycles of the machine.

- 5 The cam disk, which has been described as loosely mounted upon the shaft 43 is provided with ratchet teeth upon its face which are engaged by corresponding teeth formed on the inner surface of a head 44 yieldingly held in place upon the end of the shaft 43 by a spring plunger 62 connected to a spring 64 as shown in Fig. 2. The head 44 has a sliding pin connection with the shaft 43 so that it will turn with the shaft but may move longitudinally with respect thereto. The lever 58 is provided with a dog 66 which is designed to fit in the notches of the cam disk 56 and prevent reverse rotation thereof. It will be seen, therefore, that each time the shaft 43 is oscillated the cam disk 56 will be advanced one step in a counter-clockwise direction but that in the reverse movement of the shaft the cam disk will be held by the dog 66, the teeth of the head 44 then clicking over the ratchet teeth of the cam disk. In this way the cam disk 56 is moved to present alternately in successive cycles of the machine a notch or a high portion beneath the roller 66 and the stop 54.
- 10 The heel parts to be attached are presented in operative position by mechanism now to be described. Provision is made for rotatably mounting a hub 70 at the rear of the die plate 4. The hub, as shown in Fig. 6, carries a pair of spring fingers 72 which are designed to hold the leather deck of the heel. Disposed at right angles to the fingers 72 is the holder for the rubber section. This holder comprises a spanker plate 74 and a retaining rim or flange 76 secured thereto and shaped to engage the periphery of the rubber section as shown in Fig. 7. The spanker plate 74 is perforated to receive the shanks of the drivers 78 each of which, as shown in Fig. 7, is provided with a reduced shank and an enlarged head adapted, when the spanker plate is forced against the tread surface of the rubber section, to drive the heads of the attaching nails beneath the surface of the rubber. In the initial position of the machine the fingers 72 are positioned to hold a leather deck beneath the driver passages of the die plate while the rubber section is held in a position at one side.
- 15 After the attaching nails have been driven from the die plate through the leather deck the holder is turned through 90° and the rubber section is presented in the position formerly occupied by the leather deck.
- 20 The jack comprises a base 14 shaped to slide in the ways of the jack carriage 12 and having sockets to receive downwardly extending stems which are formed on the body part 86 of the jack. A pair of springs 87 normally tend to elevate the body part
- 25 above the base. On each side of the jack are arranged two pairs of vertical toggle links 88 connected at their lower ends to the base 14 and at their upper ends to the body part 86 of the jack. On both sides 70 of the jack the knuckle of each pair of toggles is connected by a bar 89 and upon the right side of the jack is provided a handle 90 by which the operator may break or straighten the toggles to lower or elevate 75 the jack. When the toggles are broken, as shown in Fig. 9, the body portion of the jack rests upon the base 14 by which it is rigidly supported. When the toggle links are straightened, as shown in Fig. 8, they 80 act to support the body part 86 rigidly a predetermined distance above the base. The adjustment of the jack here described compensates for the increased thickness of the work due to the presentation of the rubber 85 section of the heel as will be apparent from Figs. 8 and 9.
- 30 Gage mechanism is provided for positioning the shoe upon the jack and this mechanism is arranged for vertical adjustment 90 with the body part 86 of the jack. To this end there is provided a slide 99 having a pair of downwardly extending pins 97 arranged to slide freely through vertical bearings formed in a bracket 98 extending upwardly and rearwardly from the base 14. A pin 96 extends rearwardly from the body part 86 of the jack through an aperture in the slide 99 and in this way maintains a connection between the slide and the body 100 part 86 in all positions of the jack. The slide 99 carries a pair of pivotally mounted side clamps 104 extending upwardly and shaped to engage the counter portion of the shoe adjacent to the rand crease. The slide 105 99 also carries a rod 106 carrying at its upper end a back gage 108. The position of the back gage from front to rear is determined by the position of an adjustable rod 110 having a head through which passes 110 the rod 106. The rod 110 is journaled in a bracket secured to the machine frame and provided with an adjusting nut 112 by which it may be moved to locate properly the rear end of the shoe. It will be seen 115 that when the body part of the jack is lowered by moving the handle 90 rearwardly the slide 99 and all the gages carried by it are correspondingly lowered and when the body part of the jack is elevated the gages 120 are also elevated.
- 35 In the normal operation of the machine the shoe is jacked and the leather deck presented in operative position. The operator then depresses the treadle 38 to measure the 125 work. At this time the stop 54 of the movable support 8 is effective, a high part of the cam disk being beneath the roller 60, as shown in Fig. 3. The operator then starts the machine whereupon the cross head de- 130

scends and the cams 42 and 46 are rocked to elevate the support 8. It will be apparent that on account of the relatively incompressible nature of the leather deck a relatively small movement of the support 8 will be sufficient to subject the work to the required pressure. This is exactly what takes place because the stop 54 brings about a considerable initial separation of the abutment 6 and support 8 so that only the last portion of the movement of the oscillatory cams 42 and 46 is effective in elevating the support 8. In the continued downward movement of the cross head the pressure cams are first turned and, when the work is under pressure, the drivers 20 drive the attaching nails downwardly through the leather deck and the outsole as shown in Fig. 8. During the downward movement of the cross head and the working movement of the pressure cams the cam disk 56 is advanced one step so that a notch instead of a high part comes beneath the roller 60 and when the machine comes to rest the stop 52 instead of the stop 54 determines the position of the support 8. The holder is now turned by the operator to present the rubber section in the position previously occupied by the leather deck and the operator swings the handle 90 rearwardly thus lowering the jack sufficiently to compensate for the added thickness of the work. The treadle 38 is then depressed to measure the work as before and the machine again set in operation. In this cycle the oscillation of the cams 42 and 46 effects a considerably greater movement of the support 8 and on account of the flexible nature of the rubber section this greater movement results in no more than the required pressure. In this operation the shorter attaching nails with which the rubber section has been previously loaded are forced into the leather deck 100 and their heads are embedded below the surface of the rubber. During this cycle the cam disk 56 has been advanced another step so that when the machine comes to rest it is in readiness to operate again upon a leather deck.

In order to prevent the presentation of a leather deck in operative position when the pressure mechanism is set for the combined leather and rubber sections safety mechanism which will now be described is provided.

The outer end of the lever 58 is connected to a vertically extending rod 82 which carries at its upper end a finger 83 extending toward the holder for the heel section. Upon the holder at the opposite side of the hub 70 from the rubber section holder is a short bar 80 which is arranged to swing in such a path that it will be encountered by the finger 83 when the inner end of the lever 58 occupies one of the notches in the cam disk 56, that is, the position corresponding to maxi-

mum pressure. It will be seen that the operator is thus prevented from presenting the leather deck until the pressure mechanism is properly adjusted, this being usually effected by causing the machine to make an idle cycle 70 of operations.

Having thus described my invention, I claim as new and desire to secure by Letters Patent of the United States:

1. A machine for operating on heels, having, in combination, relatively movable work pressing members, means for moving one of said members to apply a measuring pressure to the work, and automatically acting mechanism for subsequently moving one of said members through greater and lesser distances alternately in successive cycles of the machine for applying additional pressures. 75 80

2. A machine for operating on heels, having, in combination, relatively movable work pressing members, means for presenting successively in operative position a plurality of heel parts, and mechanism for automatically imparting pressure applying movements of different amounts to one of the work pressing members. 85 90

3. A machine for operating on heels, having, in combination, relatively movable work pressing members, means for presenting a leather heel part and then a rubber heel part in operative position, and mechanism acting automatically on one of the pressing members to move said member through a small distance after the leather heel part is positioned and then through a greater distance after the rubber heel part has been positioned. 95 100

4. A machine for operating on heels, having, in combination, a die plate and jack arranged for relative movement, means for moving one of said members toward the other, to measure the work, and power driven mechanism for further moving the same member alternately greater and lesser distances in successive cycles of the machine. 105 110

5. A machine for operating on heels, having, in combination, work pressing members, one of which is stationary and the other movable, means for presenting a leather heel part and then a rubber heel part in operative position, and power driven mechanism for moving the movable member through a predetermined distance to press the leather heel part and then through a greater distance to press the combined heel parts. 115 120

6. A machine for operating on heels, having, in combination, work pressing members, one of which is stationary and the other movable, one being also shaped to sustain a shoe, means for presenting to the heel seat of a shoe a leather heel part for attachment and then a rubber heel part, work measuring mechanism, and power driven means for moving the movable member through a relatively short distance to press the leather heel 125 130

- part and through a relatively long distance to press the combined heel parts.
7. A machine for operating on heels, having, in combination, relatively movable work 5 pressing members, means for presenting in operative position first a leather heel part and then a rubber heel part, power driven mechanism for moving one of the pressing members after each presentation to press the work, the movement of said member being alternately long and short, and means for insuring that the leather heel part alone shall not be subjected to the longer movement of the pressing member.
- 10 15 8. A machine for operating on heels, having, in combination, relatively movable work pressing members, a carrier for presenting in operative position first a leather heel part and then a rubber heel part, power driven 20 mechanism for moving one of the pressing members after each presentation to press the work, the movements of said member being different in extent in successive cycles of the machine, and means for preventing the presentation of a leather heel part when said 25 mechanism is set for other than a short movement of the pressing member.
9. A machine for operating on heels, having, in combination, a die plate and jack 30 arranged for relative movement, mechanism for effecting such movement, a controlling cam shaped to vary the extent of successive movements, and means for independently adjusting the extent of the alternate movements.
- 35 10. A machine for operating on heels, having, in combination, a die plate and jack arranged for relative movement, mechanism for effecting such movement, a pair of adjustable stops for determining the initial 40 relative position of the die plate and jack, and automatic mechanism for rendering the stops alternately effective.
11. A machine for operating on heels, having, in combination, a die plate and jack 45 arranged for relative movement, a supporting member for one of said elements arranged to be moved to a predetermined position in each cycle of the machine, a pair of independently adjustable stops for determining the initial position of said support and consequently its effective movement, and means for rendering the stops alternately effective.
12. A machine for operating on heels, having, in combination, a die plate and jack 50 arranged for relative movement, a supporting member for the jack, a pair of stops on said support, means for moving the support to a predetermined point from an initial 55 position determined by one of the stops, and a movable controlling member arranged to render said stops operative alternately in successive cycles of the machine.
13. A machine for operating on heels, having, in combination, a die plate and jack 60 arranged for relative movement, alternately acting stops for determining the extent of such relative movement, a cam disk having alternate high and low points arranged in 65 line with one of the stops, and means for moving the cam disk one step in each cycle of the machine.
14. In a heel attaching machine, a spanker plate having a rigidly attached holder 70 shaped to embrace the periphery of a rubber heel section, and separate drivers set in the spanker plate, each having a reduced shank shaped to fit into an opening in the spanker plate and an enlarged head adapted 75 to drive the attaching nails below the surface of the rubber heel section.

In testimony whereof I have signed my name to this specification.

JOHN F. STANDISH.
